GEORGE HADFIELD, OF CINCINNATI, OHIO.

Letters Patent No. 70,088, dated October 22, 1867.

IMPROVEMENT IN SURGICAL CUPS.

The Schedule referred to in these Letters Patent and making part of the same.

TO WHOM IT MAY CONCERN:

Be it known that I, GEORGE HADFIELD, of Cincinnati, Hamilton county, Ohio, have invented a new and useful Improvement in Surgical Cups; and I hereby declare the following to be a full, clear, and exact description thereof, reference being had to the accompanying drawings, making part of this specification.

My improvement consists in the provision of a broad, impervious, and highly flexible lip, of prepared caoutchouc, or gum-elastic, made applicable to the margin of a surgical "cup," whether intended for "dry cupping" or to be used in connection with scarification, vapor, or other medical agent; and the special beneficial object of my invention is complete atmospheric exclusion, without any deleterious pressure upon and consequent constriction of the capillaries, which always accompanies the use of the common surgical cup.

I have selected for illustration the application of my invention to "dry cups" designed for use in connection with an air-pump, as pertaining to the class of cupping apparatus for which my invention is more particularly intended.

Figures 1, 2, and 3 are axial sections illustrative of my improvement in its application to cups of various shapes, the same letters referring to like parts in the several figures.

The cup A may be of the represented or of any approved form, and may be furnished with a screw-neck or other coupling for the attachment of the suction pipe of an air-exhausting pump. A flange, C, which projects all around the mouth of the cup, serves to hold a broad and highly flexible lip of caoutchouc E. The flexible and greatly extended sole or bearing surface e of the lip enables it to effectually exclude the external air, without the painful and injurious local pressure caused by the rim or margin of the common surgical cup. The lip is susceptible of ready removal whenever it may be desired to cleanse, repair, or change the cups. The margin of the cup may have a concave, convex, or other form, so as to fit any specific part or member of the human body.

I claim here as new, and of my invention—

The provision for surgical cups of the broad, flexible, and impervious lip E e, formed and adapted to operate in the manner described.

In testimony of which invention I hereunto set my hand.

GEO. HADFIELD.
